UNITED STATES PATENT OFFICE.

JAMES R. RICKETTS, OF LOS ANGELES, CALIFORNIA.

STOVE.

1,130,930.

Specification of Letters Patent.

Patented Mar. 9, 1915.

Application filed January 24, 1914. Serial No. 814,086.

To all whom it may concern:

Be it known that I, JAMES R. RICKETTS, a citizen of the United States, residing at Los Angeles, in the county of Los Angeles, 5 and State of California, have invented a new and useful Stove, of which the following is a specification.

This invention relates to a gas stove for heating rooms, and one of the main objects 10 is to cause the heat to be thrown forward and downward.

Another object is to provide for circulating the air into contact with a large heated surface before it passes from the stove, and 15 to keep the air which is heated and which enters the room, separate from the fumes from the burner, and to cause the fumes to be delivered to a flue and discharged, so that the fumes do not enter the room.

20 Another object is to provide for readily filling the water pan without removing the same from the stove.

Other objects and advantages will be brought out in the following description.

25 Referring to the drawings: Figure 1 is a front elevation of a gas stove constructed in accordance with this invention with the outer casing shown as broken away and partly in section. Fig. 2 is a vertical section on line x^2-x^2 , Fig. 1. Fig. 3 is a cross section on line x^3-x^3 , Fig. 2. Fig. 4 is a section on line x^4-x^4 , Fig. 2.

The stove comprises an outer casing 1 which is preferably cylindrical as shown, 30 with a bottom horizontal wall 2, supported by legs 3. The outer casing 1 has an entrance 4 to admit air to the combustion chamber 5 which is located immediately above the bottom wall 2. Within the casing 1 is an inner chamber comprising a cylindrical wall 6 forming with the outer casing 1 an annular air space 7 and a horizontal wall 8 is arranged at an intermediate point in the cylinder 6. The extreme lower 40 end of the cylinder 6 terminates as at 9 at a point somewhat above the bottom wall 2 and the cylinder has an opening 10 in the front of the lower end thereof opposite the burner 11.

45 The burner 11 is supplied from a fuel inlet pipe 12 and 13 is a pilot light arranged over the front part of the burner 11 in a convenient position for lighting, and is supplied from a pipe 14.

50 15 is a hinged door giving ready access

to the combustion chamber 5 for lighting the pilot light 13 and may be provided with a transparent panel to allow easy inspection of the flame.

The fumes from the burner are prevented 60 from passing directly up by the wall 8 and are thrown downwardly thereby and caused to pass forward through the cutout portion 10 and then they pass upward through the annular space 7 with an oblique rearward 65 movement and pass out of the annular space through the outlet 16, which communicates with the chimney, not shown. This heats the bottom wall 2 and front part of the stove 70 very hot.

A series of air tubes 17 extend from the bottom wall 2 to the wall 8 and serve to conduct air from the room up through the tubes 17 into the space within the inner cylinder 6 above the wall 8, this air in passing upward through the tubes 17 being heated. In order to make the tubes 17 sufficiently hot, burner 11 is formed with a series of concavities 18 which receive the tubes 17 and extend part way around the same, 80 thereby very highly heating the inner half portion of each tube 17. The heated air after passing from tubes 17 is not allowed to pass directly upward, but encounters a baffle plate 19 which deflects this air toward 85 the center and then it is deflected outwardly by another baffle plate 20, and a third baffle plate 21 again deflects the air inwardly. The air then passes out through perforations 22 in a plate 23 which forms the upper 90 end of the stove and is supported by lugs 24, a curved flange 25 being provided to form a finished appearance for the top of the stove, and to also act to deflect the heat which is allowed to pass out underneath the 95 lower rim thereof. Depending from the plate 23 is a water tube 26 and below the water tube 26 is a water pan 27 with an overflow pipe 28. Lugs 29 support the water pan and bolts 30 which rest on the water pan support the three baffle plates 19, 20 and 21.

100 Water may readily be poured directly down the water tube 26 into the pan 27 so that sufficient moisture may always be given off into the room.

105 What I claim is:

110 1. In a stove, an outer chamber, an inner chamber, a bottom wall for each of said chambers, a combustion chamber, a burner

in the combustion chamber, the lower front part of the wall of the inner chamber having a cut-out portion opposite the burner, leaving a depending portion of the wall of the 5 inner casing, the bottom wall of the inner chamber being located above the burner and forming the top of the combustion chamber and with the depending portion of the said inner casing wall causing the products of 10 combustion to be drawn downward and forward against the adjacent wall of the outer casing.

2. In a stove, an outer chamber, an inner chamber, a bottom wall for each of said 15 chambers, a combustion chamber, a burner in the combustion chamber, the lower front part of the wall of the inner chamber having a cut-out portion opposite the burner, leaving a depending portion of the wall of 20 the inner casing, the bottom wall of the inner chamber being located above the burner and forming the top of the combustion chamber and with the depending portion of the said inner casing wall causing the products 25 of combustion to be drawn downward and forward against the adjacent wall of the outer casing, a pilot above the burner and a fuel pipe leading under the burner to the pilot light.

3. In a stove, an outer chamber, an inner chamber, a bottom wall for each of said 35 chambers, a combustion chamber, a burner in the combustion chamber, the lower front part of the wall of the inner chamber having a cut-out portion opposite the burner, leaving a depending portion of the wall of 40 the inner casing, the bottom wall of the inner chamber being located above the burner and forming the top of the combustion chamber and with the depending portion of the said inner casing wall causing the products 45 of combustion to be drawn downward and forward against the adjacent wall of the outer casing, and a series of air tubes extending from the bottom wall of the outer chamber to the bottom wall of the inner chamber.

4. In a stove, an outer chamber, an inner chamber, a bottom wall for each of said 50 chambers, a combustion chamber, a burner in the combustion chamber, the lower front part of the wall of the inner chamber having a cut-out portion opposite the burner, leaving a depending portion of the wall of 55 the inner casing, the bottom wall of the inner chamber being located above the burner and forming the top of the combustion chamber and with the depending portion of the said inner casing wall causing the products 60 of combustion to be drawn downward and forward against the adjacent wall of the outer casing, and a series of air tubes extending from the bottom wall of the outer chamber to the bottom wall of the inner chamber, said burner having a se- 65

ries of cavities which partially receive the respective air tubes.

5. In a stove, an outer chamber, an inner chamber, a bottom wall for each of said 70 chambers, a combustion chamber, a burner in the combustion chamber, the lower front part of the wall of the inner chamber having a cut-out portion opposite the burner, leaving a depending portion of the wall of 75 the inner casing, the bottom wall of the inner chamber being located above the burner and forming the top of the combustion chamber and with the depending portion of the said inner casing wall causing the products of combustion to be drawn downward 80 and forward against the adjacent wall of the outer casing, and a series of air tubes extending from the bottom wall of the outer chamber to the bottom wall of the inner chamber, the outer chamber being provided with an outlet for the passage of products of combustion from the space between the outer and inner chambers.

6. In a stove, an outer chamber, an inner chamber, a bottom wall for each of said 90 chambers, a combustion chamber, a burner in the combustion chamber, the lower front part of the wall of the inner chamber having a cut-out portion opposite the burner, leaving a depending portion of the wall of 95 the inner casing, the bottom wall of the inner chamber being located above the burner and forming the top of the combustion chamber and with the depending portion of the said inner casing wall causing the products of combustion to be drawn downward 100 and forward against the adjacent wall of the outer casing, and a series of air tubes extending from the bottom wall of the outer chamber to the bottom wall of the inner 105 chamber, a series of baffle plates above the bottom of the inner chamber and a plate at the top of the stove, the upper part of the stove being provided with outlets for the passage of heated air.

7. In a stove, an outer chamber, an inner chamber, a bottom wall for each of said 110 chambers, a combustion chamber, a burner in the combustion chamber, the lower front part of the wall of the inner chamber having a cut-out portion opposite the burner, leaving a depending portion of the wall of 115 the inner casing, the bottom wall of the inner chamber being located above the burner and forming the top of the combustion chamber and with the depending portion of the said inner casing wall causing the products of combustion to be drawn downward 120 and forward against the adjacent wall of the outer casing, and a series of air tubes extending from the bottom wall of the outer chamber to the bottom wall of the inner chamber, a series of baffle plates above the bottom of the inner chamber, a plate at the top of the stove, the upper part of the stove 125

being provided with an outlet for the passage of heated air, a water pan above the bottom of the inner chamber, and a tube extending down toward said water pan from

5 the top plate of the stove.

In testimony whereof, I have hereunto

set my hand at Los Angeles, California, this
14 day of January, 1914.

JAMES R. RICKETTS.
